UNITED STATES PATENT OFFICE

119,677

DESIGN FOR A COWLING FOR AN AIRPLANE ENGINE

Lewis E. Reisner, Dearborn, Mich., assignor to
Aviation Manufacturing Corporation, Chicago,
Ill., a corporation of Delaware

Application November 13, 1939, Serial No. 88,205

Term of patent 7 years

To all whom it may concern:

Be it known that I, Lewis E. Reisner, a citizen
of the United States, residing at Dearborn, in the
county of Wayne and State of Michigan, have
invented a new, original, and ornamental Design
for a Cowling for an Airplane Engine, of which
the following is a specification, reference being
had to the accompanying drawing, forming a part
thereof.

In the drawing:

Figure 1 is a plan view of a cowling for an air-
plane engine, embodying my new design; and

Figures 2 and 3 are front elevational and per-
spective views of the cowling, respectively.

I claim:

The ornamental design for a cowling for an air-
plane engine, substantially as shown.

LEWIS E. REISNER.
